UNITED STATES PATENT OFFICE.

WILLIAM E. WHITE, OF CHICAGO, ILLINOIS, ASSIGNOR TO KALMAN STEEL COMPANY, OF CHICAGO, ILLINOIS, A CORPORATION OF DELAWARE.

STRIP FOR ROADWAYS.

Application filed February 8, 1926. Serial No. 86,831.

My invention relates to monolithic road construction, and particularly to a novel parting strip for use in such roads.

It is customary in the construction of 5 concrete roadways to imbed metallic strips continuously along the center line of the road, the function of the strip being well understood. Such strips are made up of successive strip sections, each of considerable 10 length, usually about 15 feet, and the ends are commonly overlapped and held in desired position by stakes.

However, a construction in which the 15 strips are overlapped is objectionable in some States where the requirement is made that the plastic concrete be routed out adjacent to the top of the strip, a suitable tool being employed that straddles and rides on the upper margin of the strip. An object 20 of this invention is, therefore, to provide means for accurately positioning and holding the adjacent ends of the strips by interlocking telescoping engagement.

A construction such as described has another 25 advantage; the extreme end of a strip may be firmly held in position by means of a stake at that end and an extension strip may be applied thereto at the proper time without disturbing the holding stake previously 30 driven. This is not possible where overlapping of the strip is practiced.

The strips are, as stated, relatively long and flexible, and as a means for facilitating the registry of the ends of the two strips, I 35 construct the upper and lower tongues of the interlock of greater length than the intermediate tongue. This feature, in connection with the V-shaped channel construction of the strip, insures a ready inter-engagement 40 of the parts.

The invention will be more readily understood by reference to the accompanying drawing, in which;

Fig. 1 is a side elevation of a strip section; constructed in accordance with my invention;

Fig. 2 is an enlarged fragmentary side elevation of an end thereof;

Fig. 3 is an end view;

Fig. 4 is a top plan view, and

Fig. 5 is a similar view of two strip sections in interlocking engagement;

The improvement sought to be covered herein relates to the means employed for effecting interlocking engagement of adjacent

strip sections in exact alignment. The improvement is preferably applied to a strip of common form, such as shown in Fig. 1, consisting of upper and lower webs, 10, 11, and an intermediate channel portion of generally V-shape, and composed of the web members, 12, 13. The purpose of the channel is to provide tongue-and-groove interlocking of the monolithic sections between which the strip is located; thus the form of the channel is unimportant, so long as the desired result is secured.

However, as heretofore stated, it is desirable to avoid overlapping engagement of the strips at the junction of adjacent sections, and to this end I provide at one end only of each section, a plurality of tongues, 14, 15, 16, preferably formed as integral extensions from the webs constituting the strip. In the form shown, the tongues are alternately laterally deflected on opposite sides of the plane of the material from which the tongues are projected, the tongues 14, 16, being in the same alignment while the tongue 15 is on the opposite side. The extent of deflection is equal to the thickness of the material of the strip. The tongue 14, is formed as an extension of the webs, 10, 12, of the channel, being terminated short of the top edge of the strip in order that an ample depth of single thickness material is provided at the joint. This permits the continuous travel of the finishing tool over the joint. This is not essential to the bottom edge and therefore the tongue 16, is formed as an extension of a part of the web, 13 and of the entire web, 11. The tongue, 15, is formed as an extension of both the webs, 12, 13, and is, therefore, V-shaped in end elevation. As shown the ends, 17, 18, 19, of the tongues, are bevelled outwardly, and the center tongue is shorter than the upper and lower tongues in order to assist in effecting the end to end interlocking abutting engagement of the sections. The holes, 20, provided in the channel portion are for the reception of the holding stakes, and it will be noted that a stake may be driven to accurately position the extreme end of the strip before an extension strip is added. This is not possible where the strips are overlapped and held by a stake.

It is obvious that the specific location and arrangement of the tongues may be varied

without lessening the substantial advantages resulting from the employment of the disclosed principles, and I do not wish to be limited except as indicated in the appended claims.

I claim:

1. A road strip of channel form and a plurality of tongues projecting from the end of the strip, said tongues being alternately deflected oppositely from the body of the strip, the upper of said tongues being below the top edge of the strip.
2. A road strip of channel form and a plurality of tongues formed as an extension of the channel portion of the strip, said tongues being alternately displaced laterally into planes on opposite sides of the

plane of the material from which they are displaced the upper of said tongues being located a substantial distance below the top edge of the strip.

3. A road strip having a V-shaped longitudinal channel, and tongues extending from the channel portion at one end, one tongue being provided at each angle of the V, said tongues being alternately displaced on opposite sides of the plane of the body of material composing the channel, the upper tongue being below the upper edge of the strip and the lower tongue extending to the bottom of the strip.

In testimony whereof I have affixed my signature.

WILLIAM E. WHITE.
